JACOB DOURSON, OF COLUMBUS, OHIO.

Letters Patent No. 88,146, dated March 23, 1869.

IMPROVED SOFA-BEDSTEAD.

The Schedule referred to in these Letters Patent and making part of the same.

To all whom it may concern:

Be it known that I, JACOB DOURSON, of Columbus, in the county of Franklin, and State of Ohio, have invented a useful and improved Portable Sofa-Bedstead; and I do hereby declare the following to be a full, clear, and exact description thereof, sufficient to enable those skilled in the art to which my invention appertains, to fully understand and use the same, reference being had to the accompanying drawing, forming part of the specification, and in which—

Figure I is a front view of my sofa.

Figure II, an end view of the same.

Figure III, a rear view.

Figure IV, a transverse vertical section.

Figure V, a side elevation of the sofa, adapted as a bedstead.

Figure VI, an end view of the same.

Figures VII, VIII, and IX, detail views to be herein-after more fully described.

My invention is an improvement in that class of sofas which can, by a simple adjustment, be adapted for use as bedsteads.

My invention consists mainly in the construction and arrangement of a hinge, which so connects the parts together that the sofa may be readily converted into a bedstead, or packed for transportation.

Similar letters of reference indicate corresponding parts in the several figures.

In the drawings—

a a represent the end-pieces of the sofa, having vertical posts *b b* at the front.

To the rear sides of these end-pieces, posts *c* are attached by any suitable hinges, *d d*.

End-pieces *e*, like those marked *a*, are hinged in the same manner to the posts *c*.

The mattress-supporting frame is made of longitudinal strips, *f f*, and transverse end-strips.

These latter are each made in sections *h i j k*, jointed together, as shown.

Longitudinal slats *l* are fixed to the end strips.

On the inner face of each end piece *a a*, *e e*, I fix horizontal ledges, *m m*.

On top the ledges *m* of the end pieces *a*, the sections *h* of the jointed end strips are supported, and secured to said end pieces *a* by means of a single screw, if desired.

The remaining sections *i j k* are not attached to the head and foot-boards.

By reference to Figs. I, II, III, and IV, it will be seen that when in use as a sofa, the sections *k* of the jointed strips, together with the side strip *f* and slats *l*, are adjusted, so as to occupy a vertical position, and there supported by the end pieces *e*, which are folded back, as shown in Fig. III.

When the sections *k* are turned up, the parts *i j* occupy the positions shown in Fig. IV.

To convert the sofa into a bedstead, the end pieces *e* are turned out straight, and the sections *k*, with the strip *f* and slats, first folded down on top the stationary parts *h*, (the intermediate sections permitting this) and then turned back to a horizontal position, so as to rest on the ledges *m* of the end pieces *e*.

To adapt the bedstead for use as a sofa, the parts *k*, with their attachments, are first folded down on to the fixed sections *h*, and then raised, a downward pressure being at the same time exerted on the strips *f*, which causes the parts to assume the position shown in Fig. IV, where they are sustained by the end pieces *e*, folded in, as before.

During these several adjustments, it is not necessary to remove the mattress, which may be so made as to serve both as a bed for the bedstead and as a seat and back for the sofa.

In Fig. IX is shown a fastening for holding the parts of the bedstead together.

a represents the piece which is secured to the posts, and

b c d are different views of the piece which goes through the end rail of the mattress-frame.

To pack the sofa-bedstead for transportation, the end pieces are detached from the mattress-frame, which is folded together, enclosing the mattress, if desired.

The head and foot-boards are also folded.

By constructing the hinge in sections, *h i j k*, I am enabled to bring the back down to the usual height of a sofa, and also to bring part of the mattress-frame down below the seat of the sofa.

The sofa-bedstead can be made as ornamental as desired, and its construction is such, that when in use as a sofa, there is nothing unusual in its appearance.

The advantages of my invention will be appreciated on account of the simplicity of construction and the ease with which the sofa may be converted into a bedstead, and vice versa.

Having thus described my invention, What I claim as new, and desire to secure by Letters Patent, is—

1. The hinge of the mattress-frame, made in sections *h i j k*, jointed together, substantially as herein described, for the purposes set forth.

2. The combination of the mattress-frame, having jointed end pieces, and the folding head and foot-sections, constructed substantially as and for the purposes herein set forth.

JACOB DOURSON.
